G. S. O'NEIL,
AUTOMATIC CLOSURE CONTROLLING APPARATUS.
APPLICATION FILED FEB. 17, 1921.

Patented July 19, 1921.

2 SHEETS—SHEET 2.

UNITED STATES PATENT OFFICE.

GEORGE S. O'NEIL, OF PATERSON, NEW JERSEY.

AUTOMATIC CLOSURE-CONTROLLING APPARATUS.

1,385,093.

Specification of Letters Patent. Patented July 19, 1921.

Application filed February 17, 1921. Serial No. 445,742.

To all whom it may concern:

Be it known that I, GEORGE S. O'NEIL, a citizen of the United States, residing at Paterson, in the county of Passaic and State 5 of New Jersey, have invented certain new and useful Improvements in Automatic Closure-Controlling Apparatus, of which the following is a specification.

This invention relates to automatic means 10 for controlling movable closures, and its principal object is to provide a simple, reliable, inexpensive and readily applied means for bringing about the closing of, for example, a window sash at any appointed 15 time.

In the accompanying drawings—

Figure 1 is an inside view of a window sash and its frame with my apparatus applied thereto;

20 Fig. 2 is a side elevation, partly in section;

Fig. 3 is a sectional view of the dog and 25 detent of the tripping mechanism of my apparatus; and

Fig. 4 shows my apparatus arranged to 30 control both a sash and the dampers of a furnace.

a designates the sash and *b* the frame in 35 which it is arranged to move up and down in the usual way. The sash is preferably provided with means which tends to overcome the usual counter-weights (not shown) and urge it downwardly; in the present instance this means is shown as a cylindrical holder *c* which is suitably secured upon the sash within the groove *d* in the frame *b* in which it travels and in which may be placed any number of weights *e*, but any other expedient for normally urging the sash 40 downwardly may be adopted.

A controlling member *f*, in the present case in the form of a cam lever, is pivoted to a suitable bracket *g* which is attached to the frame *b*. This lever is so arranged that its 45 shorter arm, which is preferably shod with a rubber pad *f'*, is adapted to bear against the inner face of the sash, at which time the lever stands at an upwardly oblique angle to said face of the sash.

50 There is a bracket *h* attached to the inner face of the frame *b* and to this is suitably secured a clock *i* having an actuating member *i'* which may be set to move at a given time; if the clock is an ordinary alarm 55 clock member *i'* may be its alarm winding key or an extension thereof. On bracket *h*

are also arranged the detent and dog of means adapted to be tripped and controlling the lever or member *f*. The bracket has a laterally extending arm *h'* in which is pivoted the detent, *j*, whose right-hand end, underlying and adapted to be impinged and pressed downwardly by the member *i'* of the clock, is normally held elevated by a spring *k*; in the bracket is also pivoted a dog *l*, 60 substantially a bell-crank lever, having a short upturned arm adapted to bear at its inner side against the end of the detent and a long laterally projecting arm which underlies the detent. 70

Another bracket *m* is affixed to frame *b* below bracket *h* and in this is fulcrumed a lever *n*. One arm of this lever is connected by the flexible connection *o* with the long arm of the dog *l*; its other arm is connected 75 with the long arm of the controlling member *f* by a flexible connection *p* which includes a spiral spring *q*.

The control of furnace dampers may also be effected by the apparatus above described. 80 Thus (Fig. 4) *A* and *B* indicate the dampers of a furnace made one to open when the other closes through the intermediary of a suitable lever *C* and connections *D*. *E* is a hook for holding lever *C* in position to retain damper *B* open and allow damper *A* to then close, the lever being weighted so that when released from the hook it will allow damper *B* to close and open damper *A*. A flexible connection *F* extends from 85 hook *E* over a pulley *G* and has a ring *H* and a weight *I* attached to its free end. The ring may be hooked over a pivoted arm *J* which is held horizontally, in position to support the weight, by a flexible connection *K* extending up to that arm of lever *n* to which connection *o* is attached, *i. e.*, when lever *n* is itself held in the position shown in full lines by dog *l* and detent *j*; when lever *n* shifts to the dotted line position arm 90 *J* falls and the weight *I* descending the position of the dampers is reversed, as will be 95 apparent.

The sash having been raised to the desired height the operator shifts the dog *l* to the 100 full-line position in Fig. 3, upon which the detent will spring in position to hold it there. The movement of the dog has, through the described connections, caused the rubber-shod end of member *f* to bear 110 against the sash thus by friction to retain the latter at the elevation to which it has

been moved. When member i' of the clock i is released at the predetermined time it impinges detent j and moves it clear of dog l which, falling, releases lever f and permits 5 the sash to fall. Spring q not only imposes a certain amount of desirable tension on dog l when it is held by the detent but makes it unnecessary to set the brackets g , h and m in always precisely the same spacing from 10 each other. Lever f acts substantially as a cam to prevent upward movement of the sash so that it cannot be opened further than the distance set. On the other hand said lever will allow the sash to be pushed 15 down even when the lever is in the holding position; this is an advantage when some other element than the sash is to be controlled, as the furnace dampers A and B , and it is desired to close the sash and leave 20 the other element under time control. An additional advantage of spring q is that it permits lever f to be moved to allow the sash to be raised without disturbing lever l and consequently the dampers.

25 Having thus fully described my invention, what I claim is:

1. In combination, with supporting means, a controlling member having movement therein back and forth and its movement in 30 one direction limited thereby, elastic trippable means normally holding said member at said limit, and time means for tripping said trippable means.

2. In combination, a fixed structure, a closure movable therein, a controlling member for the closure having movement in said structure back and forth and having its movement in one direction limited by the closure, and elastic trippable means normally 35 holding said member at said limit.

3. In combination, a fixed structure, a closure movable therein, a controlling friction brake member for the closure having movement in said structure back and forth and

having its movement in one direction limited 45 by the closure, and elastic trippable means normally holding said member at said limit.

4. In combination, a fixed structure, a closure movable therein, a controlling cam member for the closure having pivoted 50 movement in said structure back and forth and having its movement in one direction limited by the closure, and elastic trippable means normally holding said member at 55 said limit.

5. In combination, a frame structure, a sash movable up and down and normally urged downwardly in said structure, a controlling member normally engaging the sash and opposing greater resistance to upward 60 than to downward movement thereof, said member being movable in the frame structure away from the sash, and trippable means normally holding said member engaged with the sash.

6. In combination, a frame structure, a sash movable up and down and normally urged downwardly in said structure, a controlling member normally frictionally engaging the sash and opposing greater resistance to upward than to downward movement thereof, said member being movable in the frame structure away from the sash, and elastic trippable means normally pressing 70 said member against the sash.

7. In combination, with the movable member to be controlled, said member having limited movement, a pivoted dog, an elastic connection between said member and the dog, said dog being movable to a definite 80 position and thereby acting through said connection to hold said member at said limit, a detent for holding said dog in said position and movable to clear the same, and time means controlling the detent.

In testimony whereof I affix my signature.

GEORGE S. O'NEIL.
